UNITED STATES PATENT OFFICE.

ALFRED JOHNSON, OF DETROIT, MICHIGAN.

OVERSHOE.

1,276,928.

Specification of Letters Patent. Patented Aug. 27, 1918.

Application filed October 11, 1917. Serial No. 196,055.

To all whom it may concern:

Be it known that I, ALFRED JOHNSON, a citizen of the United States of America, residing at Detroit, in the county of Wayne 5 and State of Michigan, have invented certain new and useful Improvements in Overshoes, of which the following is a specification, reference being had therein to the accompanying drawings.

10 This invention relates to overshoes, and has special reference to a sole protecting device in contradistinction to an overshoe that incloses or covers the heel portion of a shoe.

15 The primary object of my invention is to provide a shoe sole protecting device that may be easily and quickly slipped or fitted on to the sole of a shoe and clamped in engagement therewith so as not to become accidentally displaced while being worn.

20 Another feature of my invention is to furnish a sole protecting device with a gripping member that will retain the side edges or flanges of the device in engagement with 25 the edges of a shoe sole, and with a clamping device that may be easily and quickly actuated to lock the protecting device on the shoe sole.

25 A further object of my invention is to accomplish the above result, by a simple, durable and inexpensive construction that will be hereinafter specifically described and then claimed, and reference will now be had to the drawing, wherein—

30 Fig. 1 is a side elevation of a shoe provided with the sole protecting device, which is partly broken away and partly in section;

35 Fig. 2 is a bottom plan of the same, showing the clamping device in an open position by dotted lines;

40 Fig. 3 is a perspective view of a portion of the shoe sole protecting device, illustrating a gripping member, and

45 Fig. 4 is an enlarged cross sectional view of a portion of the shoe sole protecting device, showing the use of a sealing member.

50 In the drawing, the reference numeral 1 denotes a plate conforming in plan to the shape of a shoe sole 2, and said plate has the 55 side and front edges thereof formed with an upstanding inturned wall or flange 3 adapted to snugly engage the side edges of the sole 2 and extending thereabove and in proximity to the toe cap and upper 4 of the shoe. The upper edges of the wall or flange 3 is formed with a barrel or bead 5 and

mounted therein is a piece of rigid wire 6 having the ends thereof bent to provide loop portions 7 and 8. The loop portions 7 permit of the ends of wire being stitched or otherwise fastened to the inner side of the flange or wall 3 and the loop portions 8 extend inwardly and are adapted to engage on the upper edges of the shoe sole 2 and cooperate with said wall or flange in retaining the device in engagement with the shoe sole. It is preferable to give the piece of wire 6 a slight twist before connecting the ends thereof to the wall or flange 3, so that said piece of wire will be sprung inwardly 70 and thus tend to hold the upper edges of the flange or wall in engagement with the upper of the shoe. The piece of wire 6, together with the looped portions 8 thereof constitute a gripping member around the sides or 75 walls of the plate 1 for holding said plate in engagement with the shoe sole 2.

80 The inner end of the plate 1 terminates in a tongue 9 and the wall or flange 3 has its ends merging into or terminating at said tongue. Connected to the lower face or outer side of the tongue 9 is a metallic member 10 and this member is in the form of a disk that may be countersunk in the tongue 9 and connected thereto by prongs 11 extending through the tongue and clenched on the inner or upper face thereof.

85 Pivots connected to the member 10, centrally thereof as at 12, is a lever 13 and pivotally connected to said lever, equi-distant from the pivot 12, are the inner ends of clamping arms 14. The arms 14 are slidably in staples or guides 15, carried by the tongue 9, and the outer ends of said arms are shaped to engage the sole 2 at the instep portion 90 or arch of said sole, the outer ends of the arms being somewhat hook shaped so as to engage the upper projecting edge of the shoe sole.

95 The outer end of the lever 13 terminates in a handle portion 16 that is resilient and may be sprung into engagement with a side edge of the arched sole 2 adjacent the heel of the shoe. In this manner, the lever 13 may be locked against accidental movement, 100 and with the clamping arms 14 in a closed position on the shoe sole 2, said clamping device positively holding the tongue 9 against the arched portion of the sole 2 and with the plate 1 in proper position to be 105 safely worn.

110 The plate 1 and its walls or flanges 3 may

be made of rubber or a material similar to an ordinary overshoe, so as to protect the shoe sole 2 from dampness, mud, water or the elements. The protecting device is water proof and as contributing toward the further protection of the shoe sole, the inner side of the wall or flange 3 may be provided with a sealing or packing member 17 that may be placed under compression when the 10 protecting device is placed on the shoe sole, to seal the connection between the wall or flange 3 and the upper of the shoe, thus preventing mud, sleet or water from entering any space that may exist between the plate 1, and the wall or flange 3, and the shoe sole or upper.

For other purposes than that of using the protecting device to exclude dampness or rain from the shoe sole, the plate 1 of said 20 device may be made of metal, fire proof or indurate material, so as to protect a workman's shoe from hot or rough surfaces.

One embodiment of my invention has been illustrated but it is to be understood that the 25 structural elements are susceptible to such variations and modifications as fall within the scope of the appended claims.

What I claim is:—

1. A shoe sole protecting device comprising a plate having an inturned wall adapted 30 to engage the side edges of a shoe sole, a gripping member in the upper edges of said

wall and having end portions adapted to overlie the side edges of a shoe sole, clamping arms on the inner end of said plate 35 adapted to engage the side edges of a shoe sole, and means connected to said arms and adapted to engage the side edge of a shoe sole to hold said arms in engagement therewith. 40

2. An overshoe comprising a plate adapted to engage and inclose a shoe sole, clamping arms slidable on said plate and adapted to engage the side edges of the shoe sole at the arched portion thereof, and a lever connected to said arms adapted to engage a side edge of the shoe sole and hold said clamping arms in engagement therewith.

3. An overshoe comprising a plate having side walls adapted to inclose the side edges 50 of a shoe sole, and a member in the side walls of said plate to cause said side walls to snugly engage the upper of the shoe, said member having the ends thereof shaped for attachment to the side walls of said plate 55 and to overlie the upper side edges of the shoe sole.

In testimony whereof I affix my signature in the presence of two witnesses.

ALFRED JOHNSON.
